APPARATUS FOR FILLING TINS WITH A
GAS HEAVIER THAN AIR

Carl Loehle, Zurich, Switzerland

Application July 8, 1931, Serial No. 549,503
In Switzerland September 8, 1930

5 Claims. (Cl. 226—68)

The present invention relates to an apparatus for filling tins containing solid victuals, tobacco, etc., with an inert gas heavier than air.

It is of great importance for the preserving of victuals, tobacco, etc., to have an inert gas instead of air in the interstices of the contents of the tins. If the inert gas is heavier than air, it is possible to displace the air from the tins by letting an inert gas flow into them. As this process needs a certain time, it is only possible to utilize the full capacity of the sealing machine by employing an apparatus, in which several tins can be exposed to the influence of the inert gas at the same time and for a certain length of time.

The drawings represent apparatus made according to the present invention and suitable for the indicated process.

Fig. 1 is a longitudinal section diagrammatically representing an apparatus with a container, and Fig. 2 shows a cross-section on the line II—II of Fig. 1.

Fig. 3 is a plan view, and Fig. 4 is a cross-section on the line IV—IV of Fig. 3, of a further example of the invention.

Fig. 5 represents a cross-section on the line V—V of Fig. 6 and Fig. 6 is a plan view of a variation of the last example of the invention.

Fig. 7 shows a cross-section on the line VII—VII of Fig. 8, and Fig. 8 is a plan view of another example.

Referring to Figs. 1 and 2, the container 1 is provided with a band 4 supported by rollers 2 and 3. This band carries the tins from left to right. A tin to be filled with gas is put into the container at the left end. The tin at the right end is provided with its cover and passed into the sealing machine. The gas enters through a tube 6.

The apparatus shown in Figs. 3 and 4 is supposed to contain an installation, not indicated in the drawings, for carrying the tins in the direction of the hands of a clock. The tin 5a has gone through almost the whole circular way of the container 1, and, being ready to be sealed, is taken out through an opening in the cover. The tin 5b to be filled with gas is put into the container. The gas enters through a tube 6.

The apparatus shown in Figs. 3 and 4 can be advantageously modified, so that the container itself carries the tins in the circular way, as shown in Figs. 5 and 6, which represent cross-sectional and plan views respectively. The container 1 is provided with a rail 7, which is supported by rollers 8 provided with a flange 9. The rollers are supported by brackets 10 on columns 11. The columns also carry the cover 12, which

closes the container, but does not touch it, in order not to prevent its rotation. At least three columns 11 are required, which can be connected with one another by small crossbeams 13. The cover has an opening for putting in and taking out the tins. The rotating movement can be effected by hand utilizing handles 14, or by any mechanical apparatus.

If the diameter of the container is small, it may be advantageous to omit the inner wall. In this case, the apparatus is diagrammatically represented in Figs. 7 and 8 in cross-section and plan view respectively. The container 1, into which the tins 5 are placed, is provided with a rail 7 carried by rollers 8, which are provided with a flange 9. The rollers are supported on brackets 10 on columns 11. The columns carry the cover 12, which closes the container, but does not touch it, and which has an opening for putting in and taking out the tins and through which the pipe 6 extends to near the bottom of the container for supplying gas as described above. At least three columns 11 are required, which can be connected with one another by small crossbeams, for which the brackets 10 are enlarged. In this case it is possible to rotate the container about a central pivot.

What I claim is:

1. Apparatus for filling tins containing victuals, tobacco, etc., with a gas heavier than air at atmospheric pressure; comprising a container with closed side walls and a cover therefor, means adapted to support the tins in a continuous movement, at least one filling and emptying opening being provided in said cover, and means for supplying gas to the tins.

2. Apparatus for filling tins containing victuals, tobacco, etc., with an inert gas heavier than air at atmospheric pressure; comprising a container with closed side walls and a cover therefor, means adapted to support the tins in a continuous movement in said container, at least one filling and emptying opening being provided in said cover, and means for supplying gas to the tins.

3. Apparatus for filling tins containing victuals, tobacco, etc., with an inert gas heavier than air at atmospheric pressure, comprising a horizontal container of rectangular cross-section having closed side walls and a cover, a band supported on rollers and adapted to carry the tins from one end of the container to the other, two filling and emptying openings being provided in the cover, and means for supplying gas to the tins.

4. Apparatus for filling tins containing vict-

- 5 uals, tobacco, etc., with an inert gas heavier than air at atmospheric pressure, comprising a horizontal cylindrical container of rectangular cross-section with closed side walls, rollers supporting said container to enable it to rotate about its vertical axis, a stationary cover on the container provided with at least one filling and emptying opening, and means for supplying gas to the tins.
5. Apparatus, for filling tins containing vict-

uals, tobacco, etc., with an inert gas heavier than air at atmospheric pressure, comprising a horizontal circular trough with closed side-walls and a cover, the trough being supported on rollers and adapted for rotating about its vertical axis, said cover being stationary and provided with at least one filling and emptying opening and means for supplying gas to the tins.

CARL LOEHLE.
